UNITED STATES PATENT OFFICE.

STEPHEN SMITH, OF PHILADELPHIA, PENNSYLVANIA, ASSIGNOR TO HORNER BROTHERS, OF SAME PLACE.

DESIGN FOR A CARPET.

SPECIFICATION forming part of Design No. 14,938, dated April 1, 1884.

Application filed February 27, 1884. Term of patent 3½ years.

To all whom it may concern:

Be it known that I, STEPHEN SMITH, of Philadelphia, State of Pennsylvania, have invented and produced a new and original Design for Carpets, of which the following is a specification.

The nature of my design is fully represented in the accompanying photographic illustration, to which reference is made.

I claim as my invention—

The design for a carpet, as shown.

Witnesses: STEPHEN SMITH.

WILLIAM ROYAL,
BENTON O. SEVERN.
